Substitute for application Serial No. 605,741,
April 16, 1932. This application September 21,
1936, Serial No. 101,833

17 Claims. (Cl. 170—172)

This application is a substitute for my application Serial No. 605,741, filed April 16, 1932 which became abandoned on January 20, 1934.

This invention relates to a propeller for aircraft. In my co-pending application Serial No. 98,772, filed August 31, 1936, I have shown a propeller in the operation of which air is drawn into a circular revolving head and is thrown out at high velocity through restricted openings at its periphery in a direction to carry it past an annular plate which projects radially outward beyond the openings but is out of line with the openings. An annular pocket is formed between this plate and the head, and the air stream passing over this pocket causes a partial vacuum to be created in said pocket and over the annular plate and atmospheric pressure causes the air stream to be deflected toward the plate. The air stream and centrifugal force co-act to remove the pressure from the forward side of the plate and atmospheric pressure on the opposite side of the plate and head tends to move the propeller forward.

In the present invention, instead of throwing the air radially outward over an annular plate, I provide a head which may be attached to a propeller shaft and a plurality of wings equally spaced apart circumferentially of the head, each wing projecting laterally outward from the head and having a plurality of funnels for catching the air as the head rotates. These funnels, which are on the forward part of each wing and extend transversely thereof, have their outlet ends spaced from the base plate of the wing by a wall which forms a pocket between said ends and said plate. The air issuing at high velocity from these funnels passes over the pocket and is deflected by atmospheric pressure toward the rear part of the plate and the air flowing over and past the plate and pocket removes the pressure from one side of the plate and atmospheric pressure on the opposite side tends to lift the propeller or force it forward.

In the accompanying drawing,

Fig. 1 is a front end view of the propeller;
Fig. 2 is a side elevation of the same; and

Fig. 3 is a section through one of the propeller wings, taken on the line 3—3 of Fig. 1.

For convenience in the use of terms, the propeller will be described as a lifting propeller, although it is intended to be used either for lifting or pulling. Referring to the drawing, *a* indicates a hollow head, to the base of which is attached a coupling *b* by which the head may be attached to the end of a propeller shaft. The form of the head may vary, but preferably it is conical, its

outer surface sloping at an angle of approximately 45° to its axis, as shown in the drawing. A plurality of wings *c*, evenly spaced apart circumferentially of the head, project laterally outward from its base, each wing being inclined forwardly with respect to the direction in which the propeller rotates, which direction is indicated by the arrow in Fig. 1. Each wing comprises an oblong base plate *1* which extends laterally outward from the head, flush with its base, the rear part *1a* of the plate curving slightly downward, as shown in Fig. 3. Upon the base plate is arranged a plate *2*, one edge of which is welded to the forward or leading edge of the plate *1*, the meeting edges of the plates being indicated at *3*. The plate *2* inclines upwardly and rearwardly from its forward edge and the rear part *2a* of the plate extends substantially parallel with the plate *1* and is supported by a flat strip *4* which forms a wall extending from end to end of the wing. The part *2a* of the plate *2* projects rearwardly a short distance beyond the wall *4*, as shown, thereby forming a pocket *5* between the plates at the rear of the wall. The several plates and the wall *4* extend to the surface of the conical head and are suitably joined thereto. Partitions *6*, evenly spaced apart, are arranged transversely on the plate *2*, and a top plate *7* is secured to the upper edges of these partitions. The partitions are approximately concentric with the axis of the head. An end plate *8* extends across the outer end of each wing, the forward part of this plate fitting against the ends of the base, intermediate and upper wing plates *1*, *2* and *7*, and the wall *4*, and the rear part *8a* of the plate *8* curves slightly outward and extends to the rear edge of the base plate, the top edge of said rear part sloping or curving from the upper plate to the base plate, as shown. The partitions and the intermediate and upper plates form a series of funnels *c'*, *c''*, *c'''* and *c''''*, the larger ends of which are at the forward or leading edge of the wing, while the smaller ends of the funnels project over the supporting strip *4*, which is about midway between the front and rear edges of the base plate *1*. Each wing is preferably inclined slightly downwardly from the base of the head, as shown in Fig. 2 of the drawing.

In operation, the propeller is rotated very rapidly and the air which enters the funnels through their larger ends is highly compressed in the funnels and issues with high velocity from their smaller ends. As the air issues from the funnels, it is drawn downwardly toward the rear

half of the base plate and flows over and past the rear edge of the plate. In issuing from the hoppers, the air jets are also carried outwardly over the base plate by centrifugal force, so that 5 the air issuing from the jets flows downwardly toward the rear part of the base plate and diagonally over it, passing off at its rear edge.

My theory of the operation of the propeller is that the high velocity air streams passing over 10 the pocket 5 cause a partial vacuum to be created in said pocket and atmospheric pressure causes the streams to be deflected downwardly over and past the rear half of the base plate, the air streams acting to remove the air pressure from 15 the upper side of the plate, thereby creating a difference in atmospheric pressure on opposite sides of the plate, which tends to lift the wing. I do not, however, wish to confine myself to any particular theory of operation.

20 What I claim is:

1. An air-craft propeller comprising a head adapted for connection to a propeller shaft and a plurality of wings spaced apart circumferentially of the head, each wing comprising an ob- 25 long base and top plates extending laterally from said head, the top plate being of less width than the base plate and extending over the forward part of the latter, and spaced partitions forming transverse air passageways between said 30 plates, the discharge ends of said passageways being spaced from the base plate.

2. An air-craft propeller comprising a head adapted for connection to a propeller shaft and a plurality of wings spaced apart circumferentially of the head, each wing comprising an ob- 35 long base plate extending laterally from said head, and funnels on the upper side of the plate having their larger ends facing the direction of motion of the wing and their smaller ends ar- 40 ranged to discharge air rearwardly above the rear portion of the plate.

3. An air-craft propeller comprising a head adapted for connection to a propeller shaft and a plurality of wings spaced apart circumferentially of the head, each wing comprising an ob- 45 long base plate extending laterally from said head, and funnels on the upper side of the plate having their larger ends facing the direction of motion of the wing and their smaller ends ar- 50 ranged to discharge air rearwardly above the rear portion of the plate, the smaller ends of the funnels being spaced from the plate.

4. An air-craft propeller comprising a head adapted for connection to a propeller shaft and a plurality of wings spaced apart circumferentially of the head, each wing comprising an ob- 55 long base plate extending laterally from said head, funnels on the upper side of the plate having their larger ends facing the direction of motion of the wing and their smaller ends arranged to discharge air rearwardly above the rear portion of the plate, and a wall between the plates adjacent the discharge ends of the funnels.

5. An air-craft propeller comprising a head adapted for connection to a propeller shaft and a plurality of wings spaced apart circumferentially of the head, each wing comprising an ob- 65 long base plate extending laterally from said head, and funnels on the upper side of the plate having their larger ends facing the direction of motion of the wing and their smaller ends arranged to discharge air rearwardly above the rear portion of the plate, the upper walls of said funnels inclining from the forward ends rear- 70 wardly toward the plate.

6. An air-craft propeller comprising a head adapted for connection to a propeller shaft and a plurality of wings spaced apart circumferentially of the head, each wing comprising an oblong base plate extending laterally from said head, 5 funnels on the upper side of the plate having their larger ends facing the direction of motion of the wing and their smaller ends arranged to discharge air rearwardly above the rear portion of the plate, and a wall between the plate and funnels, located a short distance in advance of their discharge ends, forming a pocket between the funnels and plate.

7. An air-craft propeller comprising a head adapted for connection to a propeller shaft and a plurality of wings spaced apart circumferentially of the head, each wing comprising an oblong base plate extending laterally from said head and having its rear portion inclined down- 10 wardly, and funnels on the upper side of the plate having their larger ends facing the direction of motion of the wing and their smaller ends arranged to discharge air rearwardly above the rear portion of the plate.

8. An air-craft propeller comprising a head 15 adapted for connection to a propeller shaft and a plurality of wings spaced apart circumferentially of the head, each wing comprising an oblong base plate extending laterally from said head and having its rear portion inclined down- 20 wardly, funnels on the upper side of the plate having their larger ends facing the direction of motion of the wing and their smaller ends arranged to discharge air rearwardly above the rear portion of the plate.

9. An air-craft propeller comprising a head 25 adapted for connection to a propeller shaft and a plurality of wings spaced apart circumferentially of the head, each wing comprising an oblong base plate extending laterally from said head and having its rear portion inclined down- 30 wardly, funnels on the upper side of the plate having their larger ends facing the direction of motion of the wing and their smaller ends arranged to discharge air rearwardly above the rear portion of the plate, and a wall between the plate and funnels, located a short distance in advance of their discharge ends, forming a pocket between the funnels and plate.

10. An air-craft propeller comprising a head 35 adapted for connection to a propeller shaft and a plurality of wings spaced apart circumferentially of the head, each wing comprising an oblong base plate extending laterally from said head and having its rear portion inclined down- 40 wardly, funnels on the upper side of the plate having their larger ends facing the direction of motion of the wing and their smaller ends arranged to discharge air rearwardly above the rear portion of the plate, and a wall between the plate and funnels, located a short distance in advance of their discharge ends, forming a pocket between the funnels and plate.

11. An air-craft propeller comprising a head 45 adapted for connection to a propeller shaft and a plurality of wings spaced apart circumferentially of the head, each wing comprising an ob- 50 long base plate extending laterally from said head, funnels on the upper side of said plate extending transversely thereof, the mouths of said funnels being adjacent the forward edge of the plate and the discharge ends of the funnels being adjacent and spaced from the central portion of the plate, and a wall extending longitudinally of the plate a short distance in advance of 55 said discharge ends.

12. An air-craft propeller comprising a head 60 adapted for connection to a propeller shaft and a plurality of wings spaced apart circumferentially of the head, each wing comprising an ob- 65 long base plate extending laterally from said head and having its rear portion inclining down- 70 wardly, and funnels on the upper side of said plate extending transversely thereof, the mouths of said funnels being adjacent the forward edge of the plate and the discharge ends of the funnels being adjacent and spaced from the central portion of the plate.

13. An air-craft propeller comprising a head 75 adapted for connection to a propeller shaft and

a plurality of wings spaced apart circumferentially of the head, each wing comprising an oblong base plate extending laterally from said head and having its rear portion inclining downwardly, funnels on the upper side of said plate extending transversely thereof, the mouths of said funnels being adjacent the forward edge of the plate and the discharge ends of the funnels being adjacent and spaced from the central portion of the plate, and a wall extending longitudinally of the plate a short distance in advance of said discharge ends.

13. An air-craft propeller comprising a head adapted for connection to a propeller shaft and a plurality of wings spaced apart circumferentially of the head, each wing comprising an oblong base plate extending laterally from said head, funnels on the upper side of the plate having their larger ends facing the direction of motion of the wing and their smaller ends arranged to discharge air rearwardly above the rear portion of the plate, and a plate at the outer end of the wing projecting upwardly from the base plate and extending to the rear edge thereof.

25 14. An air-craft propeller comprising a head adapted for connection to a propeller shaft and a plurality of wings spaced apart circumferentially of the head, each wing comprising an oblong base plate extending laterally from said head, funnels on the upper side of the plate having their larger ends facing the direction of motion of the wing and their smaller ends arranged to discharge air rearwardly above the rear portion of the plate, and a plate at the outer end of the wing projecting upwardly from the base plate and inclining outwardly thereon to the rear edge of the plate.

30 15. An air-craft propeller comprising a head adapted for connection to a propeller shaft and a plurality of wings spaced apart circumferentially of the head, each wing comprising an oblong base plate extending laterally from said

head, funnels on the upper side of the plate having their larger ends facing the direction of motion of the wing and their smaller ends arranged to discharge air rearwardly above the rear portion of the plate, a wall between the plate and funnels, located a short distance in advance of their discharge ends, forming a pocket between the funnels and plate, and a plate at the outer end of the wing projecting upwardly from the base plate and extending to the rear edge thereof.

16. An air-craft propeller comprising a head adapted for connection to a propeller shaft and a plurality of wings spaced apart circumferentially of the head, each wing comprising an oblong base plate extending laterally from said head and having its rear portion inclining downwardly, funnels on the upper side of said plate extending transversely thereof, the mouths of said funnels being adjacent the forward edge of the plate and the discharge ends of the funnels being adjacent and spaced from the central portion of the plate, and a wall extending longitudinally of the plate.

17. An air-craft propeller comprising a head adapted for connection to a propeller shaft and a plurality of wings spaced apart circumferentially of the head, each wing comprising an oblong base plate extending laterally from said head, and inclined in the direction of rotation of the propeller with respect to a radial line passing through the axis of the head, funnels on the upper side of the plate having their larger ends facing the direction of motion of the wing and their smaller ends arranged to discharge air rearwardly above the rear portion of the plate, the side walls of said funnels being substantially concentric with the axis of the head, and a wall between the plate and funnels, located a short distance in advance of their discharge ends, forming a pocket between the funnels and plate.
